UNITED STATES PATENT OFFICE.

SAMUEL T. ATKIN, OF GEORGETOWN, TEXAS.

DESIGN FOR A SHOE-SCRAPER.

SPECIFICATION forming part of Design No. 33,095, dated August 21, 1900.

Application filed July 21, 1900. Serial No. 24,452. Term of patent 7 years.

To all whom it may concern:

Be it known that I, SAMUEL T. ATKIN, a citizen of the United States, residing at Georgetown, in the county of Williamson, State of Texas, have invented and produced a certain new and original Design for a Shoe-Scraper, of which the following is a specification, reference being had therein to the accompanying drawings, in which—

- 10 Figure 1 is a perspective illustrating my design for a shoe-scraper. Fig. 2 is a vertical section of the same on the line $x-x$ of Fig. 1, and Fig. 3 is a similar view on the line $y-y$ of Fig. 1.
- 15 As shown in the drawings, the leading or material feature of this design consists of the parallel standards A A and the horizontally-disposed connecting-bar B, together with the oppositely-disposed concaved scraping-faces C C, extending laterally from one of the stand-

ards A. The upper ends of these standards are provided with curved caps A' and shoulders A², while the lower ends thereof are provided with lateral lugs A³, as shown. The concaved bars C at their free ends form a V-shaped recess C' and between their points of connection with the standards a triangular-shaped aperture C².

Having described my invention, what I claim as new, and desire to secure by Letters Patent, is—

The design for a shoe-scraper, substantially as herein shown and described.

In testimony whereof I affix my signature in presence of two witnesses.

SAMUEL T. ATKIN.
